UNITED STATES PATENT OFFICE

JAMES RALPH WATTS, OF NEW CASTLE, DELAWARE, ASSIGNOR TO AMERICAN MANGANESE STEEL COMPANY, OF CHICAGO, ILLINOIS, A CORPORATION OF MAINE

DIPPER TOOTH

Application filed December 17, 1928. Serial No. 326,466.

This invention relates to improvements in dipper teeth and particularly to improvements in two-part dipper teeth and in the securing means between the parts.

As shown by Patent No. 943,775 to Exton and Sherrerd, December 1, 1909, it has been common practice to form dipper teeth connected to the forward edge of the dipper front in two parts because of the fact that the end of the tooth receives the greater amount of the wear and, therefore, is made removable so that the entire tooth need not be scrapped, thereby saving the cost of the high-grade manganese steel required for the parts of the tooth. The two parts of the tooth consist of a base or shank secured to the lip of the dipper front and a removable tip or point secured to the base. Further in order to allow a longer period of use without renewal, both the base and tip are made reversible so that if the lower face of either the base or tip is worn either part may be reversed to present a new face in position to receive the wear. As shown by the patent mentioned above, the tip is provided with divergent rearwardly extending jaws which abut against a V-shaped point formed on the nose of the base member and the tip is provided with a rearwardly extending shank which enters into a receiving opening in the base member. The heavy stresses exerted laterally and transversely on the points of the teeth are prevented from shearing the shank of the point or tip by the V-shaped point of the base contacting with the divergent jaws. Furthermore, the web which connects the tip to the shank prevents the spreading of the jaws. In the construction shown by the patent, the securing means between the shank and the base member consists of a tapered bolt or pin passed transversely to the axis of the members and holding the tip by a wedging action.

It is the purpose of this invention to improve upon the securing means shown in the patent named above by providing a standard bolt and nut for connecting the tip to the base member which extends substantially along the axis of the members and is concealed within the interior of the members.

It is further the object of this invention to

so design the shank of the tip and nose of the base member that the parts may be easily and quickly assembled and secured together.

An additional object of the present invention consists in an improved construction of a dipper tooth in which a detachable and reversible tip is mounted on detachable and reversible sub-base member; the connection between the tip and the sub-base comprising a shank extending from the tip substantially rectangular in section and having its greatest depth in a vertical plane received in a socket formed in the sub-base member and secured by a standard bolt and nut connection. The shank of the tip is provided with lateral openings in order to releasably connect with the head and shank of the bolt. The sub-base member is also provided with a lateral opening into which will extend the threaded end of the bolt to receive a nut inserted through the lateral opening. The construction of the sub-base member is such that the longitudinal socket and the lateral opening open up the section of the casting to permit uniform heat treatment.

Other and further objects of this invention will be easily apparent as the improvements are more fully described.

In the drawings in which a preferred embodiment is specifically shown—

Figure 1 shows a side elevation of the dipper tooth.

Figure 2 is a vertical sectional view on line 2—2 of Figure 1.

Figure 3 is a front elevation of the dipper tooth shown in Figure 1, having the pointed tip removed.

Figures 4 and 5 are detail views of the pointed tip taken at right angles to each other.

The drawings show one form of construction of a dipper tooth corresponding to dipper teeth which have been used in this art except for the design of the shank of the pointed tip and the nose of the base member and the securing means between the two parts. Thus there is shown a shank or base member 1 having upper and lower attaching jaws 2 and 3, leaving an opening 4 therebetween to receive the front lip and having a connecting web 5 between the two jaws.

which prevents spreading and fits into a slot in the lip. The jaws are provided with openings 6 and 7 allowing the entrance of bolts to connect the base to the lip of the dipper front in the usual manner. The base member 1 is shown reversible thus after the lower face is worn it may be reversed to present the opposite face, since it is of symmetrical construction.

- 10 The nose 8 of the base member 1 is tapered and at its end is formed into a V-shaped point 9. A pointed tip 10, usually formed from high-grade manganese steel, is adapted to be secured to the nose 8. The tapered point is clearly shown in Figures 4 and 5 in which it will be apparent that there are rearwardly extending divergent jaws 11 and 12 connected by a vertical web 13 which extends rearwardly and is formed into a substantially rectangular shank 14. With the point assembled to the base, as shown in Figure 1, it is apparent that the point 10 is secured tightly against the nose 8 and the V-shaped point 9 of the nose 8 extends between the divergent jaws 11 and 12 thus preventing the shearing of the secured shank 14 due to vertical stresses. The shank 14 of the pointed tip extends within an opening 15 formed in the end of the nose 8. The opening 15 is substantially rectangular to conform to the shape of the shank 14, and, at its end, connects with a circular opening 16 which is adapted to receive the end of a bolt 17. As shown in Figure 4, the shank 14 is provided with a transverse opening 18 permitting entrance of the head of the bolt 17. The body of the bolt 17 lies in an open slot or depression 19 extending from the opening 18 in the shank 14 to the end thereof.
- 40 In order to permit the connection of a nut 21 to the screwed end of the bolt which passes through the opening 16, there is provided a transverse opening 20 in the side of the base member 1 which is widened or 45 made large enough to permit the use of an operating tool to tighten the nut 21.

The parts are assembled by resting the bolt 17 in the seat 19 provided on the shank 14 of the point 10 and passing the shank of 50 the point together with the bolt 17 longitudinally through the opening 15 of the base member 1, the end of the bolt 17 entering opening 16, meanwhile holding the nut 21 in position to be attached to the bolt 17 by 55 means extending through opening 20. Thus it will be apparent that the bolt and nut may be tightened to firmly secure the point 10 to the base member 1. The securing means consisting of the bolt 17 and nut 21 are not 60 subjected to wear since they are concealed within the interior of the nose 8 and, it is further apparent that the securing means cannot be accidentally disengaged in use. The provision of securing means extending 65 generally along the longitudinal axis of the

parts secured as shown, permits use of a standard bolt and nut instead of a special tapered bolt or pin as previously used. Furthermore, the pins previously used are liable to become deformed since they hold the shank 70 of the tip by a wedging action and are subjected to shear.

I claim:

1. In excavating apparatus, a digging tooth comprising a tooth base having inclined upper and lower faces and vertical side walls, said side walls forwardly extending beyond said upper and lower faces to form tapered noses, said base having a rectangular socket opening inwardly from between the side walls, said base also having a transverse pocket opening into said base from one side wall and a bolt receiving opening connecting said socket and said pocket, a tooth point designed to be mounted on said tooth base and including a shank to be received in said socket, diverging jaws rearwardly extending from said point having inclined upper and lower faces to cooperate with the upper and lower faces of said base, 90 said shank having a substantially T-shaped slot opening transversely into the side of said shank, a bolt connecting said shank to said base and adapted to fit into said T-shaped slot and a securing nut for said bolt adapted 95 to be inserted through the lateral pocket of said base and to be threaded to the end of said bolt.

2. In excavating apparatus, a dipper tooth comprising a detachable and reversible sub-base member and a detachable and reversible tip member said tip and said sub-base including inclined upper and lower surfaces cooperating to form a substantially wedge shaped point, the connection between said tip and sub-base comprising a shank, rearwardly extending from said tip rectangular in section and having its greatest depth in a vertical direction said shank having a longitudinal slot inwardly cut from a vertical side 110 wall and communicating with a transverse opening in said shank having a vertical dimension slightly greater than the width of said slot, said sub-base member including openings which open up the metal of the 115 base member for heat treatment and include a longitudinal socket to receive the shank of said tip and a lateral opening rearwardly spaced from the inner end of said socket and a bolt receiving opening connecting said 120 socket and said lateral opening, a standard bolt and nut connection for securing said tip to said sub-base member, said bolt fitting into the openings formed in said shank and having a threaded end of said bolt extending 125 into a lateral opening of said sub-base member in order to receive a threaded nut.

Signed at New Castle, Delaware, this 10th day of December, 1928.

JAMES RALPH WATTS. 130
